(57) **CLAIM**

The ornamental design for a container having a shoulder and flutes, as shown and described.

DESCRIPTION

FIG. 1 is a perspective view illustrating the container having a shoulder and flutes according to our new design;

FIG. 2 is an end view thereof, the side view opposite side being a mirror image thereof;

FIG. 3 is a side elevation view thereof, the opposite side being a mirror image thereof;

FIG. 4 is a top plan view thereof;

FIG. 5 is a bottom plan view thereof; and,

FIG. 6 is another perspective view thereof.
